UNITED STATES PATENT OFFICE.

JACOB P. WRIGHT, OF BARBERTON, OHIO, ASSIGNOR TO THE DIAMOND MATCH COMPANY, OF CHICAGO, ILLINOIS, A CORPORATION OF ILLINOIS.

SPLINT-SETTING MECHANISM FOR MATCH-MACHINES.

1,319,744.

Specification of Letters Patent.

Patented Oct. 28, 1919.

Application filed February 27, 1919. Serial No. 279,527.

To all whom it may concern:

Be it known that I, JACOB P. WRIGHT, a citizen of the United States, and resident of Barberton, in the county of Summit and State of Ohio, have invented certain new and useful Improvements in Splint-Setting Mechanism for Match-Machines, of which the following is a specification.

This invention relates to that class of match making machines, termed "set and dip machines", in which splints are ejected row by row from a hopper or magazine by a setting or inserting mechanism and delivered thereby to an endless traveling carrier which conveys them through appropriate dipping and drying paths. My invention has especial reference to certain improvements in the machine forming the subject of Letters Patent of the United States No. 1,000,223 dated August 8, 1911; which machine comprises a grooved setting head reciprocative beneath the splint hopper and toward and from the carrier, and an oscillatory splint-supporting frame which is maintained normally under the splint-exit-end of the hopper and against the forward end of the head by means of a spring connection, whereby during the stroke of the head toward the carrier the frame is positively swung forwardly and downwardly a quarter-turn, or substantially so, to permit the positioning of the head in splint setting relation to the carrier, and whereby during the back stroke of the head the said frame is yieldingly returned to its position beneath the hopper. The said patented machine also comprises a clearing comb which is movable into and from the splint-receiving grooves of the setting head, whereby broken and short splints are removed from the grooves during the rearward strokes of the head; which comb is positively raised by cam-actuated connections and is yieldingly depressed by a spring connection; provision being had whereby the comb is temporarily locked in raised position, against the action of the spring, when the setting head is rendered temporarily idle during the continued operation of the match carrier.

My present invention embodies means for positively operating the oscillatory splint-supporting frame during the reciprocation of the setting head; and also mechanism for positively reciprocating the comb during the operation of said head; which mecha-

nism is of such construction that the motion of the comb is discontinued when the setting head is idle and the match carrier is active; all as will be hereinafter described and claimed.

In the drawings—

Figure 1 is a side elevation of a part of a match machine embodying my invention, the splint-setting head being shown in its outer or rearward position.

Fig. 2 is a longitudinal vertical section through the setting-head and its associated parts showing their relative positions when the head is advanced.

Fig. 3 is a detail, in plan, of one of the rearward corners of the setting-head, the adjacent slide bar therefor and its guide, a part of the head being shown in section to expose one of the bolts for detachably securing said head to the slide bar.

Fig. 4 is a transverse section, as on the line 4—4 of Fig. 3.

Fig. 5 is a skeleton perspective of the setting-head and its supporting and operating parts, showing the cam-actuated lever and latch mechanism for the clearing comb. In this view the oscillating splint-supporting frame is omitted.

Fig. 6 is a sectional perspective of a portion of the setting-head, and adjuncts, showing the locking bolts retracted and the head released from its slide bars.

Referring to the drawings, 10 designates a part of the framework of a match machine; 11 a splint supply hopper thereon, and 12 a part of an endless match carrier comprising a chain of perforated plates having rack-teeth 13 with which mesh gear-wheels 14 that are driven through suitable gearing from the main shaft 15 of the machine. A setting-head 16, which is reciprocative beneath the hopper and toward and from the carrier, has a grooved upper surface adapted to receive the splints row by row from the hopper and insert their projecting ends into the succeeding rows of perforations of the carrier. The splint receiving grooves extend from end to end of the head and correspond in number and spaced relation with a transverse row of perforations in the match carrier. In the forepart of the head, for a distance somewhat less than the length of a splint, the grooves are deeper than in the remaining portion, so as to afford for the inner ends of the splints which are seated in

the deeper grooves, a shoulder or abutment, which, in the forward stroke of the head, advances such splints to and forces them into the row of holes opposed thereto in the 5 match carrier. The deeper grooves are indicated at 17 and the shallow grooves at 18.

The head is slidingly fitted to horizontal 10 guide ways in the sides of the main frame and is detachably coupled to parallel slide bars 19 which are mounted to reciprocate in suitable guides on the main frame. These 15 slide bars have crank-rod connections 20 with gear-wheels 21 in mesh respectively with similar wheels 22 on the main shaft. The connection between the head and the 20 slide bars comprises a pair of bolts 23 which are slidingly fitted to guide ways 24 in the underside of the head so as to be movable into and out of locking engagement with 25 opposing recessed portions 25 of the respective slide bars. The inner ends of the bolts are connected by means of oppositely-disposed links 26 to a crank-disk 27 on a depending hand-piece 28 carried by the head; whereby when the hand-piece is turned in 30 one direction the bolts are shot into engagement with the slide-bars 19, and when turned in the opposite direction a reverse action is had to disengage the bolts from the slide bars and thus permit the latter to reciprocate idly.

An oscillatory frame structure is mounted to swing through an arc extending beneath the splint-exit portion of the hopper and 35 toward the carrier, concurrently with the reciprocation of the setting-head, the horizontal upper portion 29 of said structure being adapted to support the forward ends of the splints while they are being ejected 40 from, and while the leading end of the head is under the exit portion of the hopper. As the head with its row of splints advances 45 toward the carrier the frame is swung substantially a quarter-turn to permit the head to travel above the frame and into sufficiently close relation to the carrier to insert the projecting ends of the splints into the latter.

The parts thus far described are, excepting 50 as hereinafter pointed out, substantially similar in construction and operation to the corresponding elements set forth in Patent No. 1,000,223 aforesaid.

According to my present invention I connect 55 the oscillatory frame directly to the setting-head by appropriate transmitting means which insures a positive and easy swinging movement of said frame by and during the reciprocation of the setting-head; whereby said head and frame can be 60 efficiently operated at a higher speed than formerly. In this instance the transmitting means comprises two counterpart pairs of links 30; one pair being arranged adjacent 65 each end of the frame. These links are

pivoted at *a* to a bracket 31 on the underside of the head, and are extended forwardly beneath and beyond the upper portion 29 of the frame, their forward ends being upwardly curved and pivoted at *b* to forwardly extending lugs 32 on the oscillatory frame. Thus the pivotal points *b* are on a higher plane than the points *a* and are above and forwardly of the axis (34) of oscillation of the frame, which axis is so disposed that in the initial forward motion of the said frame the splint-supporting portion thereof exerts a slight lifting action on the superposed splints, and then such portion as it leaves the hopper begins to swing downwardly away from the splints. By virtue of the described link connection the frame, during the initial period, travels uniformly with the setting-head, and thereafter, as the forward movement of the head continues, the travel of the frame is gradually retarded until the frame reaches its downward position. The relative positions occupied by the setting-head, the splint - supporting frame, and the link connections therefor, when the head is at the limits of its backward and forward movements, respectively, are clearly shown in Figs. 1 and 2.

Mounted directly above and transversely of the setting-head is a comb comprising a bar 36 having vertically depending pins 37, or "teeth", which correspond in number, size and spaced relation with the splint-supporting groove 17 of the setting-head and are adapted by actuation of the bar to be moved into and out of said grooves at intervals. The comb-bar, which is slidingly supported in a guide structure 38 arranged directly in the front of the hopper, is provided with projecting end studs 39 to which are pivotally connected the lower horizontal arms of bell-crank levers 40 fulcrumed on the respective ends of the hopper. The up-standing arms of the crank-levers are connected by means of links 41 with the upper ends of rock-arms 42 rising from a rock-shaft 43 which has its bearings in suitably-disposed brackets 44 on the main frame. Pursuant to my present invention the rock-shaft 43 is positively actuated through suitable connections from a continuously rotating cam 45, during the reciprocations of the setting-head, in order to insure more rapid and efficient concurrent operations of the head and comb than formerly; which shaft 120 can nevertheless be rendered inactive when the head is idle, even though the said cam and the driving mechanism of the machine be in operation.

The cam 45, which is fast on the main 125 shaft 15 of the match machine, is provided with a closed race 46 with which is engaged a stud or roll 47 on one arm of a rock-lever 48. This lever is pivoted, as at 49, to an arm 50 fast on one end of the rock-shaft 130

43; the other arm of the lever terminating in a latch-engaging tail 51 overhanging the rock-shaft. Loose on the rock-shaft is an upwardly inclined latch member 52 having 5 a locking projection 53 which is held normally engaged with the tail of the lever by means of a retracting spring 54 which is secured to the latch member and to the free end of the rock-arm 50; thereby temporarily locking the lever to the rock-arm. Hence during the continuous rotation of the cam 45 the lever and its associated rock-arm are moved as a unit, the rock-shaft 43 thus being actuated to effect the positive reciprocal 10 of the clearing comb. The contour of the cam-race is such that when the setting-head is making its back stroke from the match carrier, the comb is lowered at or about the time the inner shouldered portion 15 of the grooves 17 is directly under the teeth of the comb, which teeth thereupon enter such grooves and remain therein until the head has completed its back stroke, thus expelling all splints or pieces of splints 20 from the grooves. The cam-race then effects the raising of the comb and maintains it in position a sufficient interval of time preparatory to a succeeding descent into the grooves. 25

30 By the above-described construction it will be seen that when the latch member is disengaged from the tail of the lever 48, the latter is idly oscillated on its pivot 49 on the rock-arm; said arm and the rock-shaft 43, together with the comb, thus being unaffected by the operation of the rotating cam.

Means are provided whereby the latch member is automatically disengaged from 40 the lever when the splint-setting head is independently thrown out of action during the operation of the match machine. In the present instance, the latch member is connected by means of a link 55 to an arm 45 56 fast on a rock-shaft 57 having its bearing in a bracket 58 on the main frame. Fast on this rock-shaft is an up-standing arm 59 the upper end of which lies directly beneath and adjacent one side of the setting-head. The arms 56, 59 and their shaft 57 constitute, in effect, a crank-lever. The locking bolt on the side of the head, adjacent the arm 59 is provided with a depending tappet lug 60 which is so positioned 50 that when the head is locked to the slide bars 19 the lug, during the reciprocation of the head, passes laterally of and escapes the upper end of the arm 59, but when the bolts are disengaged from the bars, the lug 55 60 is in alignment with said arm. The bars are provided adjacent their recessed portions 25 with lugs 61 which are adapted to bear against and effect the forward stroke of the setting-head when the latter 65 is unlocked; thus insuring the movement

of the head to its advanced position adjacent the match carrier. During such forward movement of the unlocked head the lug 60 impinges against and partially turns the opposing arm 59, thus swinging the arm 70 56 and effecting the disengagement of the latch member from the tail of the oscillating lever. The arm 59 thus constitutes, in effect, a trip member for the latch. When the setting-head reaches the limit of its 75 forward stroke it comes to rest, thus locking the arm 59 in retracted position and maintaining the latch member disengaged from the lever in opposition to the action of the spring. Consequently the rock-arm 80 50 and its shaft 43 are stationary and the lever 48 is idly rocked on the arm by the cam, as previously mentioned, until the setting-head is again locked to and retracted by the slide bars. 85

It is to be understood that my invention is not limited to the specific details of construction herein shown and described, as the same may be modified within the principle of my invention and the scope of the 90 appended claims.

I claim—

1. In a match machine, the combination of a traveling carrier, a splint-hopper adjacent thereto, a splint-setting head mounted to reciprocate directly beneath said hopper, means for actuating said head, an oscillatory splint-supporting element movable through an arc extending beneath the splint-exit portion of the hopper and toward the 100 carrier, and positive transmitting means connecting the setting-head to said element and so constructed and arranged that said element is swung toward the carrier and below the path of the head during the splint-setting stroke of the head, and is returned to its position beneath the hopper during the return stroke of said head. 105

2. In a match machine, the combination of a traveling carrier, a splint-hopper adjacent thereto, a splint-setting head mounted to reciprocate directly beneath said hopper, means for actuating said head, an oscillatory splint-supporting element movable through an arc extending beneath the splint-exit portion of the hopper and toward the carrier, and positive transmitting means connecting the setting head to said element, said latter means comprising a link pivoted to said head and element and having its 110 point of connection with said element above that with the head and also above and forwardly of the axis of oscillation of said element. 115

3. In a match machine having a traveling carrier, a splint-setting head provided with grooves adapted to receive a row of splints and transfer them to the carrier, means for actuating said head, and a clearing comb for the said grooves, means, including a rock 125 130

element, for reciprocating said comb, an oscillatory member, means for positively actuating said member, and means for temporarily locking said member to the rock element.

4. In a match machine having a traveling carrier, a splint-setting head provided with grooves adapted to receive a row of splints and transfer them to the carrier, means for actuating said head, and a clearing comb for the said grooves, means, including a rock element, for reciprocating said comb, an oscillating member, means for positively actuating said member, a latch for temporarily locking said member to the rock element, and means, including a tripping member, for moving said latch into and out of locking relation to the oscillating member, locking and releasing devices between said head and its actuating means, and a tappet adapted to be positioned in operative relation to the tripping member when the said devices are shifted to release the setting-head.

5. In a match machine having a traveling carrier, a splint-setting head provided with grooves adapted to receive a row of splints and transfer them to the carrier, means for actuating said head, and a clearing comb for the said grooves, means for moving said comb into and from said grooves at predetermined intervals comprising a rock-shaft, operative connections between said shaft and comb, a rock-arm fast on said shaft, a lever pivoted on said arm, a cam for positively oscillating said lever, and means for temporarily locking said lever to the rock-arm.

6. In a match machine having a traveling carrier, a splint-setting head provided with grooves adapted to receive a row of splints and transfer them to the carrier, means for actuating said head, and a clearing comb for the said grooves, means for operating said comb comprising a rock-shaft, operative connections between said shaft and comb, a rock-arm fast on said shaft, a lever pivoted to said arm, a cam for positively oscillating said lever, a latch member for temporarily locking said lever to the rock-arm, and means, including a trip member, for moving said latch member into and

out of locking relation to said lever; locking and releasing devices between said head and its actuating means, and a tappet adapted to be positioned in operative relation to the trip member when the said devices are shifted to release the setting-head.

7. In a match machine having a traveling carrier, a splint-setting head provided with grooves adapted to receive a row of splints and transfer them to the carrier, means for actuating said head, and a clearing comb for the said grooves, means for operating said comb comprising a rock-shaft, operative connections between said shaft and comb, a rock-arm fast on said shaft, a lever pivoted to said arm, a cam for positively oscillating said lever, a latch member for temporarily locking said lever to the rock-arm, a spring normally holding said latch member in locking position, a crank-lever, a connection between one arm of the latter and the latch member, locking and releasing devices between said head and its actuating means, and a tappet adapted to be positioned in operative relation to the other arm of the crank-lever when the said devices are shifted to release the setting-head.

8. In a match machine, the combination of a carrier, means for impelling the same, a splint hopper, a splint-setting head provided with grooves to receive a row of splints from the hopper and transfer them to the carrier, means for actuating said head in coöperative relation to the carrier, a clearing comb for said grooves, mechanism for actuating said comb comprising a lever, means for positively reciprocating said lever, and releasable connections, including a trip member, for said lever and comb, locking means whereby said head may be engaged with or disengaged from its actuating means, and a tappet movable with the head and adapted to be shifted into the path of said trip member when the locking means is positioned to release the head.

Signed at Barberton, in the county of Summit, and State of Ohio, this 17th day of February, A. D. 1919.

JACOB P. WRIGHT.
